UNITED STATES PATENT OFFICE.

HARRY J. COCKS, OF DES MOINES, IOWA, ASSIGNOR TO METAL PRODUCTS COMPANY, OF DES MOINES, IOWA, A CORPORATION OF IOWA.

COIL-WINDING FORM.

Application filed September 7, 1926. Serial No. 133,835.

The object of my invention is to provide a coil winding form of the kind employed in winding coils for radio equipment.

More particularly, it is my object to provide a form of this kind of very simple, durable and inexpensive construction, having parts which can be readily and easily assembled and mounted on a rotating shaft, and which can be quickly and easily removed from the shaft.

Another purpose is to provide such a form in which the pins are mounted in such manner that they may be easily removed after the coil has been sold without injury or distortion to them or to the coil.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 is a front elevation of a coil winding form embodying my invention.

Figure 2 is a side elevation of the same; and

Figure 3 is a horizontal, sectional view taken on the line 3—3 of Figure 1.

In winding tuning coils of certain kinds for radio equipment, the coils are wound on cores or forms having a series of equidistantly spaced radially extending pins.

After the coil has been wound, the core with the coil thereon is taken from the shaft, and a rubber cement is then applied to the coil to seal the windings so that they can not separate.

Heretofore, it has been the custom to use a core, comprising a disc having a series of radially arranged holes in its circumference and to force into these holes the ends of pins in which a slot has been formed. There is enough resiliency in such pins so that when the slotted ends are forced into the holes, the pins will stick or be held by friction.

After the rubber cement has been applied, these pins must be pulled out and this is ordinarily done with a pair of pliers. Owing to the fact that the pins stick in the cylinder, the necessity for hard pulling on the pins sometimes breaks the seal of the rubber cement on the windings, thus injuring the coils. The use of a pair of pliers on the ends of the pins roughens them, so that

when they are again used for winding another coil, the rough places are likely to scrape the insulation from the wire from which the coil is wound, thus causing a short in the coil.

In order to provide a form in which these undesirable results may be eliminated and which will facilitate the proper operations necessary in winding a coil, I have provided the form herein shown.

In the accompanying drawings, I have used the reference numeral 10 to indicate generally the shaft on which the form is mounted.

The shaft has at its end a reduced spindle 11 and beyond that a smaller spindle 12.

It is thus seen that there is formed a shoulder 13 at the end of the shaft and adjacent to the spindle element 11.

The spindle member or portion 11 is provided with a suitable slot 14 for a half-moon key 15.

My improved form comprises an annular disc-shaped member 16 having in one side an annular recess 17 and having a central opening 18 to receive the spindle 11, and having a slot 19 to receive the half-moon key 15, whereby the form is locked on the shaft against rotation with relation thereto.

The disc 16 is provided with a series of radially arranged, circumferentially spaced holes 20 extending from the periphery of the disc inwardly, as shown in Figure 3. The holes 20 and the recesses 17 overlap so that pins 21 inserted into the holes 20 will project into the recesses 17 for a short portion of their length and for about half of their thickness.

The holes 20 are of such size as to allow the pins to be freely inserted and withdrawn without binding.

A locking plate or disc 22 is provided with a hole 23 to receive the reducing spindle portion 12 and is adapted to grip the inner ends of the pins 21, as shown in Figure 3 and to be locked in position by means of a wing nut 24 screwed onto the screw-threaded end of the spindle 12.

The holes 20 are made just about snug enough so that the pins can be pushed in and will not drop out of their own weight, but may be easily pulled out without any strain on them or on the coil.

In practical use, the disc 16 is placed on

the shaft with the pins inserted in it. The locking plate 22 is placed in position on the spindle member 12 and the wing nut 24 is screwed onto the spindle member 12, engaging the inner ends of the pins 21 and locking them against accidental removal.

The coil is then wound on the form, and when finally the winding is finished, the wing nut 24 is removed and the form with the coil thereon is taken off the shaft.

The plate 22 may be taken off, but the pins 21 will be held in position by their frictional engagement with the windings.

The windings are then treated with rubber cement, which is allowed to harden.

The pins 21 can then be grasped in the fingers and pulled out without any danger of roughening or injuring them and without the likelihood of injury to the coil, which would occur if the pins were so tightly held that they must be pulled out with pliers.

A device of this kind has substantial advantages over the old type of coil winding forms in the ease with which the pins may be removed, which makes it possible to remove them without injury to them and with a minimum likelihood of injury to the coil.

Some changes may be made in the details of the structure and the arrangement of the parts, and it is my intention to cover by my claims, any modified forms of structure or use of mechanical equivalents, which may be reasonably included within their scope.

I claim as my invention:

1. In a form for winding coils, an annular

disc having a central opening to receive a shaft and having a series of holes extending radially inwardly from the periphery of the disc, said disc having in one side an annular recess, a locking plate adapted to be projected into said recess having a central hole to receive a spindle, a plurality of pins having their inner ends received in said holes and projecting into said recess for portions of their lengths and portions of their diameters, and means for locking said plate in said recess for gripping and holding said pins.

2. In a form for winding coils, an annular disc having a central opening to receive a shaft and having a series of holes extending radially inwardly from the periphery of the disc, said disc having in one side an annular recess, a locking plate adapted to be projected into said recess having a central hole to receive a spindle, a plurality of pins having their inner ends received in said holes and projecting into said recess for portions of their lengths and portions of their diameters, and means for locking said plate in said recess for gripping and holding said pins, a shaft having a reduced end, and a reduced spindle on said end, said reduced end being received in the hole in the disc, and said spindle being received in the hole in the plate and being screw-threaded, and a nut on said screw-threaded end for locking said plate in position for holding the form on the shaft and locking the pins in place.

HARRY J. COCKS.
